US00D956127S

(12) **United States Design Patent** (10) **Patent No.:** **US D956,127 S**
(45) **Date of Patent:** **** Jun. 28, 2022**

(54) **PAN AND TILT HEAD**

(71) Applicant: **Shenzhen Qiming Innovation Technology Development Co., Ltd.,**
Guangdong (CN)

(72) Inventor: **Haiyang Zhang**, Guangdong (CN)

(73) Assignee: **Shenzhen Qiming Innovation Technology Development Co., Ltd.,**
Shenzhen (CN)

(**) Term: **15 Years**

(21) Appl. No.: **29/764,336**

(22) Filed: **Dec. 29, 2020**

(30) **Foreign Application Priority Data**

May 8, 2020 (CN) 202030203057.8

CLAIM

The ornamental design for a pan and tilt head, as shown and described.

DESCRIPTION

FIG. 1 is a top, front and left side perspective view of a pan and tilt head showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings illustrate portions of the pan and tilt head which form no part of the claimed design.

1 Claim, 7 Drawing Sheets
